(57) **CLAIM**

The ornamental design for a steering wheel having pedal stand, as shown.

DESCRIPTION

FIG. 1 is a top, front, left side perspective view of a steering wheel having pedal stand according to the present disclosure;

FIG. 2 is a top, rear, right side perspective view of the steering wheel having pedal stand shown in FIG. 1;

FIG. 3 is a front elevation view of the steering wheel having pedal stand shown in FIG. 1;

FIG. 4 is a rear elevation view of the steering wheel having pedal stand shown in FIG. 1;

FIG. 5 is a right side elevation view of the steering wheel having pedal stand shown in FIG. 1;

FIG. 6 is a left side elevation view of the steering wheel having pedal stand shown in FIG. 1;

FIG. 7 is a top plan view of the steering wheel having pedal stand shown in FIG. 1; and,

FIG. 8 is a bottom plan view of steering wheel having pedal stand shown in FIG. 1.
